UNITED STATES PATENT OFFICE.

FREDERICK C. JORGESON, OF CHICAGO, ILLINOIS.

SHOW-CASE CONSTRUCTION.

SPECIFICATION forming part of Letters Patent No. 633,345, dated September 19, 1899.

Application filed May 18, 1899. Serial No. 717,256. (No model.)

To all whom it may concern:

Be it known that I, FREDERICK C. JORGESON, a citizen of the United States, residing at Chicago, in the county of Cook and State 5 of Illinois, have invented a new and useful Improvement in Show-Case Construction, of which the following is a specification.

My invention relates particularly to an improvement in show-cases in the construction 10 of which plate-glass is used to a great extent.

My primary object is to provide for show-case construction a clip or fastening of improved construction for securing the glass plates together at lines where said plates meet 15 to form corners of the show-case, which fastening obviates to a large extent the necessity of drilling holes in the glass.

In the accompanying drawings the clip is 20 shown forming the joint at the meeting corners of three plates, constituting, respectively, the top, the front, and an end of the case. It readily will appear, however, that by a modification the clip may be adapted for use at the meeting edges of two plates.

25 In the drawings, Figure 1 is a view in front upper perspective of a portion of a show-case constructed according to my improvements; Fig. 2, an enlarged broken plan view showing one corner of the case with a clip in place; 30 Fig. 3, a vertical section on line 3 of Fig. 2; Fig. 4, a vertical section on line 4 of Fig. 2; Fig. 5, a bottom plan view of a clip, and Fig. 6 a broken section on line 6 of Fig. 1.

In the preferred construction the clips form 35 the sole connection between the top, the front, and the ends of the case. A suitable base and rear side are employed, the latter being provided with doors or slides, as desired.

A represents the bottom or base of the case; 40 B, the front vertical plate; C, an end plate; E, the top plate, and F the rear frame, ordinarily supplied with a slide or a hinged door for access to the case.

G represents the clip, preferably comprising 45 a flat horizontally-disposed plate a, provided with a threaded perforation a', depending flanges b c, parallel, respectively, to the front B and end C, and lugs b' c', forming, with the flanges b and c, recesses b² c² for the vertical front and end plates. Strips of felt b³ c³ are cemented to the inner faces of the flanges b and c. The lugs b' c' are capable of being

bent to or from the flanges b and c to accommodate plates of different thicknesses. A strip of felt d is cemented to the front vertical edge of the plate C, forming contact with the adjacent vertical margin of the flush projecting plate B. 55

The adjacent upper corners of the plates B and C fit into the channels b² c² and are thereby bound together. The plate a of the clip rests upon the upper edges of the plates B and C and in turn affords at its own upper surface a bearing for the top plate E to rest upon, as shown clearly in Figs. 2 and 3. 60 Strips of felt e f are cemented to the upper edges of the plates B and C, respectively, said strips commencing at the edges of the plate a, as indicated in Figs. 2 and 4, and forming with the plate an even surface contacting with the under surface of the glass plate E. The plate E is provided with a perforation g, which registers with the threaded perforation a' of the clip. A flat-headed screw g' serves to secure the parts together, 65 as clearly shown in Fig. 3. It thus appears 70 that the only part exposed above the glass top E at the front corner is the head of the screw g' and also that the only perforation through glass made in forming the joint is 75 the single perforation through the plate E. It is possible to provide the part a with means for engaging the plate, and thus dispense with the screw g', if desired. The upper surface 80 of the part a of the clip and the outer surfaces of the flanges b and c thereof are visible through the glass top plate, and these parts, together with the head of the screw, are 85 nickelated or otherwise ornamentally finished. The part a preferably has its inner edge cut 90 in the arc of a circle, as shown. The top plate E is shown secured at the rear corner to the top of the rear frame F by a screw h. Any other fastening means may be employed 95 at this point, however. The plates B and C preferably rest at their lower edges in grooves (not shown) in the base A. Where the case is not of too great length no fastenings between the plates B and E, except at the corners of the case, are necessary. If the case 100 is a long one, however, clips adapted to the purpose may be employed for connecting said plates midway of their length. Such clips would have a top formation suited to their

new location and would have but a single recess provided on their under surfaces for receiving the upper edge of the plate B.

Changes in details of construction within 5 the spirit of my invention are understood to fall within the scope of the appended claims.

What I claim as new, and desire to secure by Letters Patent, is—

- 10 1. In a show-case, or the like, the combination with the bottom and the rear wall of the case, of an end plate and a front side plate, a clip resting on said plates at their adjacent upper corners provided with flanges contacting with the outer margins of the plates, and
- 15 also provided with lugs contacting with the inner margins thereof and provided further with a vertical perforation, said lugs being susceptible of being bent to accommodate

plates of varying thicknesses, a top plate resting upon said clip having a vertical perforation, and a screw passing through the perforation of the top plate and into the perforation in the clip, substantially as and for the purpose set forth.

- 20 2. As a new article of manufacture, the clip for fastening the corners of show-cases, and the like, comprising the plate *a* having the screw-socket *a'* and provided with the edge flanges *b* *c*, and with the lugs *b'* and *c'* projecting from the face of the plate parallel 30 with the flanges, said lugs being susceptible of being bent, substantially as described.

FREDERICK C. JORGESON.

In presence of—
R. T. SPENCER,
D. W. LEE.
